UNITED STATES PATENT OFFICE.

LEONIDAS M. CHANCELLOR AND SULLIVAN D. CHANCELLOR, OF WILMINGTON, OHIO.

DIE FOR FORMING WHEEL-RIM SECTIONS.

1,069,919.

Specification of Letters-Patent. Patented Aug. 12, 1913.

Application filed June 11, 1909. Serial No. 501,489.

To all whom it may concern:

Be it known that we, LEONIDAS M. CHANCELLOR and SULLIVAN D. CHANCELLOR, citizens of the United States, residing at Wil-
5 mington, in the county of Clinton and State of Ohio, have invented certain new and useful Improvements in Dies for Forming Wheel-Rim Sections, of which the following is a specification.

10 Our invention relates to the improvement of dies for forming wheel rim sections and has particular relation to dies for the production of flaring wheel rims or sections thereof of the character usually employed
15 in the construction of wheels for corn planters and similar agricultural machines.

The objects of our invention are to provide an improved die construction by means of which an ordinary straight metal band 20 may be quickly and accurately stamped or pressed into the flaring or curved form which is desirable in the production of concave wheel rims of the class above referred to. These objects we accomplish in the
25 manner illustrated in the accompanying drawing, in which:

Figure 1 is a central vertical section through the upper and lower die members showing the upper die member out of engagement with the lower die member and showing the rim section supported by the main die member previous to the operation of shaping the same. Fig. 2 is a similar sectional view showing the upper die member in engagement with the lower die member and with the rim section curved or flared as a result of the downward pressure of the upper die section, and, Fig. 3 is a plan view of the lower die member and rim section shown in Fig. 2.

Similar numerals refer to similar parts throughout the several views.

In carrying out our invention, we employ a receiving die member 1, which is adapted 45 to be rigidly supported in a suitable manner, said die being in the nature of a circular block of hardened steel or other suitable properly hardened material, through which may be formed a central vertical
50 opening 2, the upper end portion or mouth of which is enlarged, forming at the base of said enlargement a circular shoulder or horizontal seat such as is indicated at 3. The inner circular wall surface of the die member 1 above the shoulder 3, is flared 55 outwardly from said shoulder on a prop-

erly curved line as indicated at 4, thus imparting to the enlargement or mouth of the opening 2 a curved taper.

5 represents the upper movable die section 60 or member which is adapted to be driven downward and moved upward by any suitable well known means. This upper die member is also in the nature of a ring body and in its lower half has its periphery cut 65 away or recessed to form an underside horizontal shoulder 6. From the inner circular line of the underside shoulder 6, the periphery of the lower and recessed portion of the body 5 is shaped to present an inwardly curved tapering surface such as is indicated at 7, thus converting the lower portion of the body 5 into a reduced tongue or extension portion 5^a, the outer surface or periphery of which is curved and tapered to 75 conform to the curvature and taper of the surface 4 of the die member 1. It will be observed, however, that the circumference of the tongue or extension 5^a of the member 5, is sufficiently less than the internal meas- 80 urement of the surface 4, to permit of a wheel rim section of the usual thickness being embraced between said surfaces. The tongue or extension 5^a of the member 5, is of such length and the shoulder 6 is of such 85 height, that when said tongue is in contact with the shoulder 3 of the member 1, said underside shoulder 6 is in contact with the upper side of the member 1.

In utilizing our improved die members, 90 a wheel rim section 8 is first produced in the form of a flat ring or band as indicated in Fig. 1 of the drawing. This band is seated as shown within the enlargement of the central opening of the die member 1, said enlargement being of such size as to permit of the lower portion of the band or rim section fitting snugly therein, as shown. This being accomplished, the upper die section is driven downward, the tongue portion 5^a 100 thereof, entering the band 8 and in its descent within said band, resulting through contact of the curved and tapering surface 7 with the inner side of said band, in compressing the latter until its outer surface is 105 in complete contact with the curved surface 4 of the die member 1. In this manner the rim section has imparted thereto the desired curved flaring form in cross section, such as is indicated in Fig. 2 of the drawing. 110 By this operation it will readily be understood that a previously formed metallic band

may by one operation, be converted into a flaring wheel rim section of accurate and uniform curvature and it will readily be seen that wheel rim sections formed in this 5 manner, will be of strong and durable construction.

A particular advantage in the employment of the dies described, lies in the fact that each rim produced is an exact duplicate 10 of the previously produced sections, thus facilitating the formation of concaved wheel rims of accurate construction.

What we claim, is:

Forming-dies for metal wheel rims comprising a female member having an internal 15 annular shoulder which is initially adapted

to support the metal blank, and a surrounding wall gradually flaring from the said shoulder outwardly, and a male member having a reduced extension of a convergent 20 contour and having a plane lower end constructed and adapted for movement into contact with said shoulder, said flared and convergent surfaces being of a relatively parallel curvature throughout. 25

In testimony whereof we affix our signatures in presence of two witnesses.

LEONIDAS M. CHANCELLOR.
SULLIVAN D. CHANCELLOR.
